United States Patent Office

Des. 191,123
Patented Aug. 15, 1961

191,123

TRAY

William T. Jones, Scranton, Pa., assignor to Consolidated Molded Products Corporation, Scranton, Pa., a corporation of Delaware

Filed Mar. 29, 1961, Ser. No. 64,541

Term of patent 14 years

(Cl. D44—10)

FIG.1.

FIG.2.

FIG.3.

FIG.4.

I claim:

The ornamental design for a tray, as shown.
